DESIGN FOR A CLOCK

Arnold S. Rittenberg, New Rochelle, N. Y.

Application November 1, 1935, Serial No. 59,317

Term of patent 14 years

To all whom it may concern:

Be it known that I, Arnold S. Rittenberg, a citizen of the United States, residing at New Rochelle, county of Westchester, and State of New York, have invented a new, original, and ornamental Design for a Clock, of which the following is a specification, reference being had to the accompanying drawing, forming part thereof.

Figure 1 is a front view, Figure 2 is a side view, and Figure 3 is a top view of a clock, showing my new design.

I claim:

The ornamental design for a clock, as shown.

ARNOLD S. RITTENBERG.
